James L. Jackson of New York, N.Y.
Letters Patent No 482 Dated Aug. 10th 1852

The schedule referred to in these Letters Patent and making part of the same

To all whom it may concern:

Be it known that I, James L. Jackson, of the City, County, and State of New York, have invented or produced, a new original design for a Grate frame and fender, and I do hereby declare the following to be a full, clear, and exact description of the same reference being had to the accompa-

myng drawing representing one half of the ornamental work in full, and the other half in outline only.

The outer margin of the frame which is rectangular is finished with a delicate double moulding a, and the inner margin, with a single moulding b, both of which mouldings extend entirely around the frame, to the base or pedestal of the jamb pieces. The opening in the frame for the summer piece is straight on the sides and semi-elliptical on top. From the inside extending outward from the moulding b, is a broad cavetto c, over which projects highly wrought arabesques d, with roses e, interspersed - the whole of which is flanked by a mass of highly raised gothic mouldings f, bound together by a winding band g. The corners of the frame are ornamented with a bouquet of flowers, having a full blown rose for a centre, and buds, flowers and foliage upon running vines, which extend to the extreme corners of the angular shaped panel and fills it up. The shaded line xx represents the outline of a crop section through the frame, showing the elevation of the different parts.

The fender has its centre surmounted with an arabesque figure h, and on a plain ground extending across the frame, are lozenges i, underneath which is open lace-work formed of scrolls k, and diamond work l. The ends of the fender are finished with highly wrought arabesque figures m, terminating in feet upon which it stands - the underside of the fender being, scalloped work n.

Having thus fully described and represented the nature of my design, what I claim therein as new and desire to secure by Letters Patent is the combination and arrangement of the ornamental figures herein represented forming an ornamental design for a grate frame and fender.
